(57) **CLAIM**

The ornamental design for a front cover of a scent dispenser, as shown and described.

DESCRIPTION

FIG. 1 is a front view of a front cover of a scent dispenser. FIG. 2 is a rear view thereof.

FIG. 3 is a top view thereof

FIG. 4 is a bottom view thereof

FIG. 5 is a left side view thereof

FIG. 6 is a right side view thereof

FIG. 7 is a top, left perspective view thereof

FIG. 8 is a bottom, right perspective view thereof; and, FIG. 9 is a front, right perspective view of the front cover of a scent dispenser shown in its environmental context.

Within the drawings, the broken lines are for the purpose of illustrating environmental structure and form no part of the claimed design.
